DESIGN FOR OVAL METEOR PARLOR STOVE
BY
SW. GIBBS ASS'R TO ABBOTT & NOBLE

Patented Aug. 18, 1881.

U. S. PATENT OFFICE.

No. 93.

1861.

WHOLE No. 1,458.

Parlor Stove.

SAMUEL W. GIBBS, OF ALBANY, NEW YORK,

ASSIGNOR TO ABBOTT & NOBLE, OF PHILADELPHIA, PA.

Letters Patent for a Design No. 93, dated August 13, 1861.

SPECIFICATION.

TO ALL WHOM IT MAY CONCERN:

Be it known, that I, SAMUEL W. GIBBS, of Albany, county of Albany, State of New York, have invented or produced a new and original design for Plates of a Parlor Stove, termed the "Oval Meteor;" and I do hereby declare the accompanying drawing, with the following explanation of the same, to form a full, clear, and exact description of the said design.

This design relates to that class of parlor stoves which consists of ornamented cast iron caps and bases and plain sheet iron bodies.

Fig. 1 of the drawing is a plan view of the cap.

Fig. 2, a vertical sectional view of the same, showing the form of the mouldings, there being sufficient of the exterior to illustrate the nature of the ornaments on the said mouldings.

Fig. 3 is a plan view of half of the base; and

Fig. 4, a vertical section, partly in elevation, of the base, showing the mouldings and the ornaments on the latter.

The exterior shape of the cap of the stove and its upper ornaments are clearly shown in fig. 1, the form of moulding and both upper and under ornaments being seen in fig. 2.

The rounded moulding A, which is carried entirely round and near the edge of the cap, is ornamented with a series of devices a a, situated at equal distances apart from each other, and with the star-shaped ornaments b b.

Gibbs's Design for a Parlor Stove.

The lower edge of the inner moulding B is ornamented with the pointed and other projections *d*, and the upper edge of the same moulding with the denticulated beading *ef*, being the ornamented base for the cap D of the urn, which has been illustrated and claimed in a former patent, and which has been introduced into the present drawing for the better illustration of the cap of the stove.

The concave moulding E, on the under side of the cap, has the ornaments *h* clearly shown in fig. 2 of the drawing.

The form of the base, the projection I of which forms the hearth, is shown in the half sectional plan view fig. 3. It is edged at the bottom with a moulding G, having ornaments *i* of a character somewhat similar to that of the ornaments on the moulding E of the cap, the moulding H of the base being ornamented with the devices clearly shown in fig. 4. The projecting portion I of the base has an ash-pit door J, and an air valve K, ornamented in the manner illustrated in figs. 3 and 4.

I claim the ornamental figures and forms represented in and by the accompanying drawing, and forming together an ornamental design for the cap and base of a parlor stove.

In testimony whereof, I have signed my name to this specification in the presence of two subscribing witnesses.

SAMUEL W. GIBBS.
